United States Patent Office

Des. 220,945
Patented June 22, 1971

220,945

HOUSE

Henry S. Hughes, 1320 Talbryn Drive,
Belmont, Calif. 94002

Filed Mar. 9, 1970, Ser. No. 21,808

Term of patent 14 years

Int. Cl. D25—04

U.S. Cl. D13—1

FIG. 1.

FIG. 2.

FIG. 3.

FIG. 1 is a view showing my new house design in front and one side perspective;

FIG. 2 is a similar view showing the rear and opposite side of the house; and

FIG. 3 is a view showing the transverse cross sectional shape of the house.

I claim:

The ornamental design for a house, substantially as shown.
